UNITED STATES PATENT OFFICE.

NEHEMIAH S. BEAN, OF MANCHESTER, NEW HAMPSHIRE, ASSIGNOR TO THE AMOSKEAG MANUFACTURING CO., OF SAME PLACE.

STEAM FIRE-ENGINE.

Specification of Letters Patent No. 31,138, dated January 15, 1861.

To all whom it may concern:

Be it known that I, NEHEMIAH S. BEAN, of Manchester, in Hillsboro county, in the State of New Hampshire, have invented 5 certain new and useful Improvements in Steam Fire-Engines; and I do hereby declare that the following, taken in connection with the drawings which accompany and form part of this specification, is a description 10 of my invention so full and exact as to enable those skilled in the art to practice it.

My invention relates to, and is an improvement upon, that description of steam fire engines which have a vertical boiler 15 with a tube (not necessarily cylindrical) attached to and extending therefrom at, or nearly at, a right angle with the boiler, which tube in some cases serves the purpose of a tank for the feed water to the boiler, 20 and as a bed plate for the mechanism or a part of it, and viewing the engine as a carriage or wagon the tube serves the purpose of a "perch pole" or forward part of a wagon body to which the forward wheels 25 are connected, generally so that they can turn completely under the tube.

My invention consists in the bifurcation of such a tube, and the employment of its capacity, not only for tank purposes, but 30 also for the vacuum and air chambers of the pump. The bifurcation of the tube enables me to obtain a peculiarly advantageous, well balanced, economical, and convenient, arrangement of a vertical steam cylinder 35 and pump of a fire engine, while it has the functions of the "perch pole" and bed plate as did the straight tube, while by the employment and division of the capacity of this tube for air and vacuum chambers 40 nearly all of the cost and weight of ordinary air and vacuum chambers are saved.

In the drawings similar letters refer to similar parts in the different figures, of which—

45 Figure 1, is a plan with the inner, upper, fourth part of the tube removed so as to show in section what I deem the best method of constructing it: Fig. 2, a side view, and Fig. 3, an end view of so much of a steam 50 fire engine as embodies my invention or is necessary in describing the same.

A denotes the boiler to which the tube B is secured, and C such a double acting suction and force pump as was patented to me in the United States on the 12th day of 55 June 1860. Within the tube the heads, shown in Fig. 1, divide it into compartments, the space between heads, *a* and *b* being used for a vacuum chamber, that between *b* and *c* for a water tank and that between *c* and *d* for an air chamber. The suction and delivery passages of the pump are connected with the vacuum and air chambers by the pipes *e* and *f*, which also serve to connect the pump with the tube in such a 60 manner that the piston rod of the former plays between the two parts of the tube. By this arrangement it will be evident that the vacuum and air chambers of the pump can be upon opposite sides of the fire engine in 65 harmony, and in direct communication, with the suction and delivery passages of the pump from which the hose can lead in a direct line from and to the engine, and that the steam cylinder, whose piston rod is a 70 continuation of that of the pump, can be placed directly over the pump, and may be secured wholly, or in part, to the tube or boiler or to both, the two parts of the tube serving most conveniently for the support 75 of the fly wheel shaft bearings, while the crank and other parts in immediate connection therewith play in the opening between the parts of the tube.

While the detail of the manner of the construction of the tube may be left to the ordinary skill and judgment of those skilled in the construction of steam fire engines and other mechanism of a like character, and to be modified by the circumstances of each 80 case, I will describe the detail which I practice.

The straight parts of the tube are made of wrought metal (I prefer drawn seamless brass tubes) with open ends which afford 85 facility for insertion of the heads *a* *b* *c* *d* which are fastened and secured within the tube, wherever desired, by riveting or by brazing or by both combined. The return bend I form of wrought metal, and the 100 pieces which bolt directly to the boiler are most conveniently made of castings. The

different parts forming the whole of the bifurcated tube are united with rings around the joints and by riveting or brazing or both.

- 5 Having described my invention, I claim—
As an improvement in the construction of steam fire engines, the bifurcated arrange-

ment of the tubular metallic "perch-pole" or "fore-body" whether the same is divided into compartments or not.

N. S. BEAN.
